(57) **CLAIM**

The ornamental design of a lighting fixture, as shown and described.

DESCRIPTION

FIG. 1 is a front elevational view of lighting fixture showing my new design, the rear elevational view being a mirror image;

FIG. 2 is a side elevational view thereof; and,

FIG. 3 is a top plan view thereof.

The broken-line showing of environmental structures in FIGS. 1-3 is for illustrative purposes only and forms no part of the claimed design.
